UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CONVERTIBLE-TYPE DUMP-CAR.

1,202,481.

Specification of Letters Patent. Patented Oct. 24, 1916.

Application filed April 5, 1915. Serial No. 19,171.

To all whom it may concern:

Be it known that I, ARGYLE CAMPBELL, a citizen of the United States, residing at Chicago, in the county of Cook and State 5 of Illinois, have invented a certain new and useful Improvement in Convertible-Type Dump-Cars, of which the following is a full, clear, concise, and exact description, reference being had to the accompanying 10 drawings, forming a part of this specification.

This invention relates to improvements in convertible type dump car.

An object of the invention is to provide 15 a car which may be used either as a gondola, side dump or center dump car.

Another object of the invention is to provide a car of the type above indicated which is so arranged that it will resist the buffing 20 shocks and has a center sill in addition to load carrying intermediate sills.

The invention furthermore consists in the improvements in the parts and devices and in the novel combinations of the parts and 25 devices, as herein shown, described or claimed.

In the drawing forming a part of this specification, Figure 1 is a side elevation of substantially half a car showing my im- 30 provements embodied therein. Fig. 2 is a top plan view of the car illustrated in Fig. 1 and is broken substantially at the center of the car and Fig. 3 is an enlarged detail transverse sectional view taken substantially 35 on the line 3—3 of Fig. 2, the left hand portion of Fig. 3 showing the parts when the car is arranged either for service as a gondola or for side dumping and the right hand portion showing the parts positioned 40 when the car is being utilized as a center dump car.

In said drawing, 10—10 denote the wooden side walls of the car, 11 the end sill, 12—12 the vertical side stakes, 13—13 the 45 side sills which, as shown, are in the form of channels disposed above the floor level of the car, 14—14 the load carrying intermediate longitudinal sills and 15 the center sill.

50 As shown, each intermediate longitudinal sill 14 comprises a vertical plate 16 having angles 17—17 secured to the top thereof and angles 18—18 secured to the bottom. The center sill, as shown, comprises an I-beam 55 reinforced by angles 19—19, said angles also

serving another function as hereinafter pointed out.

As will be understood by those skilled in the art, both the intermediate sills and the center sill may be constructed otherwise 60 than as I have shown, although I consider the forms illustrated as preferable. Between each intermediate sill and the side stakes are diaphragm plates 20 and between each intermediate sill and the center sill are 65 diaphragm plates 21—21, it being understood that said plates are suitably flanged to permit riveting to the sills and side stakes. The end floor of the car, as shown, is made permanent as indicated by the floor boards 70 22. Intermediate the permanent end floor portions of the car, and over what is commonly designated the hopper section of the car between the trucks, the floor of the car comprises sets of hinged floor doors 23 and 75 side dumping hinged floor doors 24. The floor doors 23 are provided with hinge straps 25 mounted on hinge pins 26 and the side dumping doors 24 are provided on their inner edges with corresponding hinge straps 80 27 mounted on the same hinge pins 26.

When the car is used for gondola service, the hinge floor doors 23 have their free or inner edges resting upon the center sill 15 and the doors 24 are held up in horizontal 85 position by suitable door operating mechanism, such for instance, as the chains 28 wound over longitudinally extending operating shafts 29 suitably mounted in bearings formed in the side stakes and other 90 bearings 30 located at the ends thereof. The operating shafts 29 are squared at their ends whereby the same may be operated by a claw bar or other suitable device and in order to lock the same, each shaft is provided with latch wheels 31 and latches 32 coöperable therewith. For side dumping, the floor doors 23 are left in the position shown in the left hand portion of Fig. 3 and the hinge doors 24 are lowered as indicated by the dotted lines on the left hand portion of Fig. 3.

When the car is utilized for center dumping, the doors 23 are swung up to the position indicated on the right hand portion of Fig. 3 at 23^A, the upper edges of the doors 23 resting against the side walls 10 of the car. The center dump hinge doors 33 are hinged at their upper edges by hinge straps 34 to hinge butts 35 secured to the center 105 110

sill 15 beneath the angle irons 19. Each door 33 has strengthening angle irons 36 at its ends and said doors are operated by means of chains 37 connected at one end to brackets 38 secured to the doors 33, said chains winding over longitudinally extending operating shafts 39 mounted beneath the intermediate sills 14. The shafts 39 are suitably mounted in brackets and are squared at their ends and provided with latch wheels and latches as indicated at 40 whereby the same are operated and locked in the usual manner. Secured to the inner side of each intermediate sill 14, near the bottom thereof, and extending between each pair of diaphragms 21, are inclined diverting boards 41, the latter being bolted or otherwise suitably secured to brackets or braces 42 which in turn are riveted to the intermediate sills and angles 18. These diverting boards serve to divert the material to points between the tracks, when the car is being utilized as a center dump car, it being understood that the rails are located directly beneath the intermediate sills 14. Each of the center dump doors 33 is provided along its upper edge with a flange 43 which serves to cover the hinges and in conjunction with the angles 19 prevents material from falling between the angles and the doors 33. As shown in Fig. 2, when the car is being used as either a side or center dump car, temporary ends may be formed at the ends of the hopper section by boards 44 which are removably held between angles 45—45 secured to the inner faces of the car sides. When the boards 44 are not being used, they may be stored by placing the same between the ends 11 of the car and angles 46—46 (see Fig. 2).

From the preceding description it will be seen that I have provided a car of the convertible type which is of strong construction, which may be readily changed from either side to center dumping, or vice versa, and wherein a center sill construction is employed in addition to the intermediate sills which center sill not only absorbs the buffing shocks in direct line with the draft rigging but is also of value on account of its vertical strength.

As will be understood by those skilled in the art, various changes may be made in the details of construction and arrangement of parts, particularly the various door operating mechanisms and constructions of the sills.

The form which I have shown and described I consider the preferable one but contemplate all changes and modifications coming within the scope of the claims appended hereto.

I claim:—

1. In a car of the character described, the combination with a car body having inter-

mediate sills with hoppers formed therebetween, and a center sill adapted to absorb buffing shocks in direct line with the draft rigging and having also a vertical strength value, of pivoted floor doors, some of said doors being adapted to cover said hoppers between the intermediate sills and being partly supported by said center sill when acting as floor members, and others of said floor doors being adapted to dump to the 75 sides of the car.

2. A car of the character described having side walls and a hopper section between the trucks, the floor of said car over the hopper section consisting of sets of hinged 80 doors, one set being adapted to swing downwardly from normal horizontal position to thereby dump the load to the sides and the other set being adapted to be swung upwardly from normal position to an outwardly and upwardly inclined position, said car having also center dump doors located below the floor level of the car and hinged along their inner upper longitudinal edges.

3. A car of the character described having side, deep intermediate sills and diaphragms, said intermediate sills having diverting boards along their lower edges, said car having also hinged center dump doors located entirely below the car floor level, 95 hinged side dumping floor doors extending between the intermediate and the side sills, and movable floor sections arranged to either cover the hopper spaces between the intermediate sills or to form inclined hopper 100 bottoms.

4. A car of the character described having intermediate sills, a single center sill, side dump doors, hinged floor doors adapted to be positioned either horizontally to form 105 part of the floor between the intermediate sills or to be positioned so as to incline upwardly and outwardly to form sides of hoppers, and center dump doors hinged along their inner longitudinal edges to said single 110 center sill.

5. In a car of the character described, having intermediate sills, a single center sill, side dump doors, hinged floor doors adapted to be positioned either horizontally to form 115 part of the floor between the intermediate sills or to be positioned so as to incline upwardly and outwardly to form sides of hoppers, and center dump doors hinged along their longitudinal edges to said single center 120 sill, said center sill having longitudinally extending plates secured thereto immediately above the hinged joints to thereby form shedding surfaces over said hinged joints.

6. A car of the character described, having intermediate sills, hinged side dumping doors, hinged floor doors adapted to form the portion of the floor between the intermediate sills, center dumping doors located 125

below the floor level, and operating mechanism for the center dump doors including two longitudinally extending shafts each located directly beneath one of said intermediate sills.

7. A car of the character described having side sills, intermediate sills, and diaphragms, said intermediate sills having diverting boards secured thereto on the inner side along their lower edges, said car being provided also with hinged center dump doors, hinged side dumping doors, and movable floor sections arranged to either cover the hopper spaces between the intermediate sills or to form inclined hopper bottoms.

8. A car of the character described having a pair of intermediate sills and a center sill forming hoppers therebetween, and hinged doors for said hoppers, one set of doors being on one side of the center sill and the other set on the opposite side thereof.

9. A car of the character described having deep intermediate sills and a load carrying center sill to thereby form longitudinally arranged hoppers therebetween, said car having also hinged hopper doors, said doors being hinged along their upper edges to said center sill.

10. In a car of the character described, the combination with deep intermediate sills and a center sill, of diverting boards secured to the inner sides of said intermediate sills along the lower edges thereof and hinged doors located below the floor level of the car, said doors being hinged along their upper edges to said center sill.

In witness that I claim the foregoing I have hereunto subscribed my name this 23rd day of March 1915.

ARGYLE CAMPBELL.
